UNITED STATES PATENT OFFICE.

WILLIAM SOMERVILLE, OF ST. LOUIS, MISSOURI.

DESIGN FOR A LANTERN-GLOBE.

SPECIFICATION forming part of Design No. 23,824, dated November 27, 1894.

Application filed August 27, 1894. Serial No. 521,461. Term of patent 14 years.

To all whom it may concern:

Be it known that I, WILLIAM SOMERVILLE, a citizen of the United States, residing at St. Louis, in the State of Missouri, have invented 5 and produced a new and original Design for Lantern-Globes, of which the following is a specification, reference being had to the accompanying drawings, forming a part thereof.

In the drawings where my new and original 10 design is shown, and where like marks of reference refer to the same parts, Figure 1 is a front elevation of a lantern globe showing my design, and Fig. 2 is a side view of the same, one-half being in elevation, and the other half 15 in section.

The features of my design consist in a lantern globe, which in cross section is round or circular having a bulbous or expanded lower end 1, and a tapering contracted upper end 20 2, of a bead or seat 3 formed around the globe near each of its open upper and lower ends, and circular concave reflectors or lenses 4, formed in the lower bulbous end 1, and on opposite sides thereof.

5 is a groove formed in the glass around 25 each of the reflectors or lenses, and 6 are beads formed on the sides of such reflectors, caused by the plane of the reflectors being at right angles with a radius of the circumference of the globe, this causing the sides of 30 the reflectors to project beyond the circumferential line of the globe while the upper and lower ends of the reflectors are about flush with the outside of such globe.

Having described my design, what I claim 35 is—

The design for a lantern globe, substantially as shown and described.

In testimony whereof I have hereunto set my hand and affixed my seal, this 10th day of 40 July, 1894, in the presence of two subscribing witnesses.

WM. SOMERVILLE. [L. S.]
